UNITED STATES PATENT OFFICE.

ABEL ARMSTRONG, OF SAN FRANCISCO, CALIFORNIA, ASSIGNOR OF ONE-HALF TO
PATRICK J. MURPHY, OF RIVERSIDE, CALIFORNIA.

ADJUSTABLE WIRE-COIL-SPRING MACHINE.

1,403,372.

Specification of Letters Patent. Patented Jan. 10, 1922.

Application filed November 6, 1920. Serial No. 422,292.

To all whom it may concern:

Be it known that I, ABEL ARMSTRONG, a citizen of the United States, residing at San Francisco, in the county of San Francisco and State of California, have invented new and useful Improvements in Adjustable Wire-Coil-Spring Machines, of which the following is a specification.

This invention relates to improvements in adjustable wire coil spring machines and relates particularly to that type of machine wherein a piece of spring wire is coiled about a mandrel for the purpose of forming a helical coil.

15 The principal object of this invention is to produce a machine which will coil a wire in a simple and efficient manner and one which will meet the requirements of the average mechanic.

20 Another object is to produce a machine which is portable and one which will produce coils of various diameters.

Another object is to produce a machine of this character wherein the convolutions of 25 the coil may be spaced one from the other to produce an open or closed spring to meet the requirements desired.

20 A further object is to produce a simple means for holding the mandrel upon which 30 the coil is to be wound and to provide accommodation for mandrels of various sizes without additional parts.

A still further object of this invention is to provide a machine which is simple in construction, compact in the arrangement of 35 its parts, positive in action, and inexpensive in manufacture.

Other objects and advantages of this invention will be apparent during the course 40 of the following description.

In the drawings forming a part of this specification and in which like numerals are employed to designate like parts throughout the same, Figure 1 is a view in side elevation, partly in cross section, of my invention.

Figure 2 is a top plan view of Figure 1.

Figure 3 is a cross section taken on the line 3—3 of Figure 1.

50 Figure 4 is a cross section taken on the line 4—4 of Figure 1.

Figure 5 is a detail view looking in the direction of the arrow on Figure 2.

Figure 6 is a detail view taken on the line 6—6 of Figure 5, and

55

Figure 7, is a perspective view of a spacer member.

In the accompanying drawings wherein for the purpose of illustration is shown a preferred embodiment of my invention, the 60 numeral 5 designates a base-plate here shown in the form of an angle iron, having one leg as at 6. The purpose of this construction is to provide means for holding the device in a vice as could be easily done by 65 inserting the leg 6 between the jaws of a vice.

It is, of course, understood that other means of supporting might be used without departing from the spirit of this invention.

70

The numerals 7 and 8 refer to tubular downward extensions, preferably formed integral with the base 5. These tubular extensions are screw-threaded as shown at 9 and provided with screw-threaded caps 11. 75 Slotted openings 12 are provided in the base-plate 5 and in alignment with the tubular extensions 7 and 8. These slots are formed parallel with each other so as to accommodate sliding supports 13. Each of the supports has a contour as is best shown in Figure 4 and carries at its lower end a screw-threaded rod 16, which passes through the caps 11, and is provided with wing nuts 17.

80 A helical spring 18 is housed within the 85 tubular portions 7 and 8 and about the rod 16 so as to abut the inner surface of the caps 11 and under-surface of the supports 13. The action of these springs is to cause the supports to be moved outwardly with respect to the tubular extensions.

85 The numeral 19 refers to a mandrel or arbor which is adapted to lie parallel to the base 5 and to be held at a pre-determined distance therefrom by the position of the 90 supports 13, the distance being regulated by the wing-nuts 17.

An opening 21 is provided in one end of the mandrel and a handle 22 is attached to the mandrel adjacent to the opening 21.

100

At the rear of the base 5 I secure a U shaped member 23, the legs of this member serving to journal a pin 24, having a wing-nut 26 thereon. This pin serves to support the bifurcated ends 27 of a spacer member 105 28. This spacer member is tapered as shown

at 29 and is beveled as shown at 31, which beveled portion together with the contours of the supports serve as means for preventing a nipping of the wire when it is being 5 formed on the mandrel.

By referring to Figures 1, 2 and 5, it will be noted that I have shown two spacer members placed adjacent to each other, the second spacer being designated by the numeral 10 32 and of lesser width than that designated by the numeral 28.

A wire guide is shown in Figures 5 and 6 at 33 and serves to guide the free end of the wire being operated upon. Assuming 15 that it is desirous of winding a spring, the operation of my device is as follows:

A mandrel of the desired internal diameter of the spring to be wound is selected and the wing-nut 17 loosened until the supports 20 13 project beyond the base 5 a sufficient distance to allow the mandrel to be inserted through the same as shown in Figures 1, 3 and 4. The wing-nuts are then tightened until the mandrel is moved toward the base 25 and is held therefrom only a sufficient distance to clear the wire to be wound upon the same as is shown in Figures 1 and 6.

A wire to be made into a spring is inserted through the wire guide 33 and into the opening 21 in the mandrel, the opening 21 being opposite the guide 33. By now selecting the proper number and widths of spacing members as shown in Figure 4 and inserting the same so that the bifurcated ends 27 straddle 35 the pin 24, a spacer may be built up of any desired width to leave between the various convolutions of the spring to be created.

By now rotating the handle 22, the wire will be coiled about the mandrel and as the 40 spacer contacts with the first convolution, it will move the mandrel forward, with the result that the mandrel will be moved forward continuously at each revolution, thereby creating an even spring.

45 It will thus be seen that I have devised a

means for winding springs, which is simple and one which will allow an amateur to wind a spring of any diameter and also one which will permit of spacing adjustment to suit the desires of the operator.

It is to be understood that the form of my invention herewith shown and described, is to be taken as a preferred example of the same, and that various changes in the shape, size and arrangement of parts may be resorted to without departing from the spirit of the invention or the scope of the subjoined claims.

Having thus described my invention I claim:

1. In a spring coiling device, a base, tubular extensions formed on said base, caps carried on said tubular extensions, supports slidable in said tubular portion and extending beyond said base, rods secured on said supports, said rods extending through said caps, means for varying the amount of extension of said supports, a mandrel carried in said supports, said mandrel being held parallel to said base, and means for spacing the convolutions of a spring being formed on said mandrel.

2. In a device of the character described, a base, tubular extensions formed on said base, caps secured to said tubular extensions, supports slidable in said extensions and projecting beyond said base, rods secured to said supports, helical springs secured on said rods, means for limiting the action of said springs, a mandrel slidably and rotatably held in said support, a U shaped support secured to said base, wire engaging means formed in said mandrel, a wire guide in alignment with said wire-engaging means, a rod carried by said U shaped support, and spacer members supported on said rod and adapted to contact with a wire being coiled about said mandrel.

In testimony whereof I affix my signature.

ABEL ARMSTRONG.
